UNITED STATES PATENT OFFICE.

FRANK S. R. PRENTISS, OF SAN FRANCISCO, CALIFORNIA.

MULTIPLE-PRINTING, DEVELOPING, FIXING, WASHING, AND DRYING APPARATUS.

No. 830,741.

Specification of Letters Patent.

Patented Sept. 11, 1906.

Application filed October 18, 1903. Serial No. 177,241.

To all whom it may concern:

Be it known that I, FRANK S. R. PRENTISS, a citizen of the United States, residing at the city and in the county of San Francisco, State of California, have invented new and useful Improvements in Multiple-Printing, Developing, Fixing, Washing, and Drying Apparatus, of which the following is a specification.

10 My invention relates to an improved apparatus for reproducing and finishing photographic prints in large quantities. Its object is to provide means whereby the successive steps of printing, developing, (or toning,) fixing, washing, and drying may be carried on continuously and to a great extent automatically in a single apparatus, and thereby do away with the manual handling of separate prints, now necessary under ordinary methods, effecting an immense saving in labor and time and producing a greater uniformity in the product.

It consists of the parts and the construction and combination of parts, as hereinafter more fully described, having reference to the accompanying drawings, in which—

Figure 1 is a side elevation of my apparatus. Fig. 2 is a plan of same. Fig. 3 is section taken on line *y y* of Fig. 2. Fig. 4 is a central section of the drier.

A represents the frame of the printing apparatus; B, the developing or toning tray; C, the fixing-tray mounted upon the rollers 2 and having a limited movement on the guides or tracks 3; D, the washing-tray, and E the drier.

The prints to be developed or toned according as a "developing-paper" or a "printing-out paper" is used are in the form of a continuous strip, (represented in the drawings by the character F.) Throughout the specification and claims it is desired that "developing-tray" or "developing-bath" be understood as the equivalent of "toning-tray" or "toning-bath."

The sensitized roll of paper or fabric to be printed on is mounted in a dark chamber 4 in frame A upon a roller 5. The end of the roll is carried between the tension-rollers 6, beneath the glass-plate 8, carrying the negative or negatives from which the positive impressions are to be printed, and over the stationary platform 7 disposed in a central opening in frame A.

The top of the platform or table 7 is covered with felt or other soft material and the paper is adapted to be moved intermittently across this surface with its film side up and adjacent to the film side of the superposed plate, the plate being lifted to allow the paper to travel forward and then being pressed down upon the paper during the printing period.

Passing over table 7 and under plate 8 the paper is received between a second pair of friction-rollers 13 into the storage-chamber 14 of frame A, whence the paper is drawn continuously through the successively arranged developing or toning, fixing, and washing baths and over the drier.

The paper is moved intermittently beneath the printing-plate 8 by any suitable means, as here shown the hand-crank 15 on one of the rollers 13.

The printing of the image upon the sensitized paper F may be done by artificial light emanating from a series of incandescent bulbs or lamps 16, carried on vertically and individually adjustable stems 17, disposed above plate 8.

From the chamber 14 the printed sheet F passes between the tension-rollers 18 into the developing-bath contained in tray or trough B and thence into the fixing-bath in tray C.

An endless carrier 19, having its horizontal portion submerged in the developing-bath, passes over roller 20 at the receiving end of tray B and around an adjustable tension-roller 21 at the rear end of the tray. A roller 22, adjacent to roller 20 and near the bottom of the tray, directs the two planes of the belt at that end into the contained bath.

A short belt 23, passing over roller 22 and a second roller 24 just above roller 20, is adapted to be driven from carrier 19 and to coöperate with the latter in guiding and feeding the strip F into the bath.

The movable fixing-tray C carries the rigid arm extensions 25 26, projecting over the developing-tray. Arm 25 carries a roller 27, which projects into tray B, and beneath the surface of the contained bath and around which the upper plane of carrier 19 passes up to and over a roller 28 on arm 26, and thence down around a second roller 29 on arm 25 to roller 21. Thus by shifting tray C back and forth on the tracks 3 space between rollers 22

and 27, and consequently the distance traversed by the developing-strip F in tray B, is lengthened or shortened according as the circumstances of the case demand at any 5 moment in the period of development. For instance, if the developing-bath is stronger at one time than at another or if one section of paper has been exposed longer than another the developing period will be comparatively 10 shorter and the fixing-carriage will be run forward by means of the crank 30, which is keyed on the shaft of one of the pairs of rollers 2. If the developing period is to be pro- 15 longed, the fixing-carriage is run backward. From roller 28 the strip F passes on to carrier 31 in tray C. Carrier 31 passes over a roller 32 under the submerged rollers 33 34 20 35, thence around an elevated roller 36 at the rear end of the tray, and over the tension- 25 roller 37. These several rollers are journaled in and movable with the frame of tray C. Also passing over these same rollers and outside of carrier 31 are a series of endless tapes 38. Intermediate, however, of rollers 36 and 37 30 they pass down and around the grooved pulleys or spools 39, carried on the ends of the swinging arms 40, which are pivoted to the carriage. These arms may be counter- 35 weightted, as at 41, to cause them normally to swing outward behind the tray C.

42 represents a series of guide-tapes passing over rollers 34, 35, and 43 and adapted to travel with carrier 31, tapes 38, and the strip F and to coöperate to keep the latter sub- 35 merged during its traverse through the fixing-bath.

From roller 36 the strip F follows tapes 38, down around spools 39, which latter cause the strip to leave the tapes and to pass film side 40 down into the washing tray or trough D and upon the carrier 44. This trough may be of any length necessary, commensurate with the speed of the machine, to wash thoroughly the printed strip and free it of all salts that might 45 tend to its deterioration.

During printing, developing, and fixing the paper is carried film side up. By making the apparatus "two-story" and returning the strip in the washing-trough beneath the 50 printing, developing, and fixing mechanism the proper inversion of the film in washing is easily effected.

From the washing-trough the strip is directed film side up again around the drum E, 55 which may be heated by any suitable means. The drum is here shown as having a hollow shaft 45, closed at one end and open at the other and having a suitable running-joint with a vapor-supply pipe 46, through which 50 heat from any convenient source of supply may be admitted to pass thence through the hollow spokes 47 to the annular space 48 between the concentric rim-sections. On leav-

ing the drier the strip is ready to be cut up and the finished prints segregated. 65

In order that the several steps of developing, fixing, washing, and drying should be continuous, means must be employed for operating the developing, fixing, and washing carriers and the drier in unison. 70

49 is a line-shaft receiving motion from any suitable source of power.

The wash-carrier 44 is driven from shaft 49 by means of bevel-gears 50, engaging corresponding gears on the rollers 51 of the wash-carrier. 75

The developing-carrier 19 and fixing-carrier 31 are driven in unison and at the same rate of speed with carrier 44 by the following means: An endless chain or belt 52 passes 80 around a sprocket or pulley on the shaft of roller 20 and over a second sprocket or pulley on a shaft 53, which latter carries a bevel-gear engaging a corresponding gear 54 on shaft 49. The shaft of roller 20 carries a 85 second pulley 55, around which passes a belt 56. The latter runs around a pulley 57 on a fixed part of the frame, and thence over a pulley 58 on shaft of roller 32 and thence around the pulley 59, carried by an adjustable arm 60 90 on the movable carriage C. Thus the developing and fixing carriers may be run constantly irrespective of the position of the carriage C on its tracks. All forward and backward movement of the carriage C is compensated 95 for by means of the pulleys 58 and 59. If in the midst of operations when the strip F is passing through the washer and over the drier it should be necessary to shift the fixing-tray forward or back to shorten or 100 lengthen the period of development, the arms 40 will swing on their pivots to maintain an equal tension on the strip and prevent its being torn.

The drier is driven in unison with the other 105 coöoperating movable parts of the apparatus by means of a bevel-gear 61 on shaft 45, engaging a corresponding gear on vertical shaft 62, which is operated from shaft 49 through the medium of suitable gearing 63. 110

The various carriers and the drier are geared up so as to carry the paper forward always at the same rate of travel.

The apparatus is thus continuous and except for the attention necessary to see that 115 development proceeds properly is practically automatic. The speed of travel of the paper during development and the successive stages is adjusted so that it will not be drawn from chamber 14 faster than it is fed thereinto. 120

I do not claim in this application the printing apparatus shown and described, as the same forms the subject-matter of a divisional application filed by me May 11, 1905, Serial No. 259,888. 125

Having thus described my invention, what

I claim, and desire to secure by Letters Patent, is—

1. The combination with developing, fixing and washing mechanisms, of means for advancing a print successively and automatically from one of said mechanisms to another of said mechanisms, and means for shifting certain of said mechanisms relative to the others to vary the time of passage of the print through the developing-bath.

2. The combination of a developing-tray, a fixing-tray and a washing-tray, carriers in said several trays, means for operating said carriers in unison, said several carriers having supporting-rollers, and means for changing the relative position of said rollers without altering the tension of the carriers.

3. In an apparatus of the class described, the combination of a series of successively-arranged baths, means for passing a print successively from one bath to another and means for shifting one of said baths relative to the other to vary the period of transmission through certain of said baths.

4. The combination with a developing-bath and a fixing-bath, of means for advancing the paper successively through said baths and means operable by the fixing-bath for varying the period of development.

5. The combination with a wash-tray, of superposed developing and fixing trays, means for shifting the fixing-tray and means for accommodating the printed strip to the movements of said fixing-tray.

6. The combination of a developing-tray, a shiftable fixing-tray, means for passing a printed strip successively from one tray to the other, a wash-tray and means by which the delivery of the printed strip into the wash-tray is adjusted to the movements of the fixing-tray.

7. The combination with a developing-bath and a fixing-bath of means for advancing the paper successively through said baths, and means operable by the fixing-bath for varying the period of development, said latter means comprising a direction-roller carried by the fixing-bath and arranged to project into the developing-bath.

8. The combination with a developing-tray and a fixing-tray of means for giving the latter a shiftable movement, and a strip-guiding means carried by the fixing-tray and arranged to be immersed in the developing-tray.

9. The combination with two successively-arranged trays through which a strip is adapted to be passed, of means for shifting one tray relative to the other, direction devices for regulating the submergence of said strip in the trays and means for maintaining uniform tension on the strip during the movement of said shiftable tray.

10. The combination with a developing-tray, and a fixing-tray through which is adapted to be passed the strip to be developed, of means for shifting one tray relative to the other, guide-rollers in the several trays arranged to effect the submergence of the strip, means for driving the several rollers in unison and means for directing the strip from one tray to the other.

11. The combination with a developing-tray, and a fixing-tray through which is adapted to be passed the strip to be developed, of means for shifting one tray relative to the other, guide-rollers in the several trays arranged to effect the submergence of the strip, means for driving the several rollers in unison and means for directing the strip from one tray to the other, certain of said rollers being carried by and movable with one tray and adapted to be submerged in the other tray.

12. The combination with a developing-tray, and a fixing-tray through which is adapted to be passed the strip to be developed, of means for shifting one tray relative to the other, guide-rollers in the several trays arranged to effect the submergence of the strip, means for driving the several rollers in unison, means for directing the strip from one tray to the other, certain of said submerging-rollers being carried by and movable with the shiftable tray but dipping into the other tray.

13. The combination with a developing-tray and a fixing-tray of means for giving the latter a shifting movement, and a strip-guiding means carried by the fixing-tray and arranged to be immersed in the developing-tray, said guiding means comprising a yieldingly-supported guide-roller.

14. The combination with a developing-tray and a washing-tray of an intermediate shiftable fixing-tray, and means for conveying a continuous printed strip or the like successively through said trays irrespective of the movements of the intermediate tray.

15. The combination of a developing-tray, a successively-arranged shiftable fixing-tray and a subjacent wash-tray and means for conveying a continuous printed strip or the like successively through said trays irrespective of the movements of the fixing-tray.

16. The combination of a developing-tray, a shiftable fixing-tray, a washing-tray, and means for directing a continuous strip or the like through the developing and fixing trays in close proximity to the bottom thereof, said means including a guide carried by the fixing-tray and projecting into the developing-tray.

17. The combination of a developing-tray, a shiftable fixing-tray, a washing-tray, means for directing a continuous strip or the like through the developing and fixing trays

in close proximity to the bottom thereof, said means including a guide carried by the fixing-tray and projecting into the developing-tray, and a yieldingly-supported guide for 5 directing the strip from the fixing-tray to the washing-tray.

In testimony whereof I have hereunto set

my hand in presence of two subscribing witnesses.

F. S. R. PRENTISS.
